UNITED STATES PATENT OFFICE.

PETER FEIDEN, JR., OF ST. JOSEPH, MISSOURI.

WHEEL-GUARD.

1,345,916.

Specification of Letters Patent.

Patented July 6, 1920.

Application filed August 21, 1918. Serial No. 250,800.

To all whom it may concern:

Be it known that I, PETER FEIDEN, Jr., a citizen of the United States, residing at St. Joseph, in the county of Buchanan and 5 State of Missouri, have invented certain new and useful Improvements in Wheel-Guards, of which the following is a specification.

This invention relates to improvements in wheel guards for railway carriages and the 10 like and one of its objects is to provide a guard of this character that can be applied to car wheels without the necessity of changing any of the parts of the car trucks. A further object is to provide a guard of this 15 type which includes a pivotally supported shoe adapted to ride over or above the rail in advance of the wheels to clear obstructions from the path of the latter and thus, in effect, to minimize liability to accidents, danger to life and limb, etc. With the foregoing and other objects in view the invention consists in the combination and arrangement of parts to be hereinafter fully described, pointed out in the appended claims and illustrated in the accompanying drawing which forms a part of this specification and in which—

Figure 1 is a view in side elevation of a wheel and the associated portion of the 30 truck with the invention applied to the truck.

Fig. 2 is a plan view of Fig. 1.

Fig. 3 is a front view of Fig. 1.

Fig. 4 is an enlarged fragmentary view 35 illustrating the gravity shoe and connections.

Like reference characters denote corresponding parts throughout the several views.

The reference numeral 1 denotes a car 40 wheel, 2 the journal box, 3 and 4 the arch bars running from the journal box to the cross beam 5. My guard proper comprises the frame 6 which is preferably formed with the knuckles 7 between which the hinge 45 leaves 8, that are carried by or secured to the journal box 2, are received, said knuckles and leaves being secured together by the pintle or hinge pin 9. The body portion of the guard is curved laterally from a point beside 50 the wheel 1 to a point in advance of the said wheel, the said guard being curved inwardly and downwardly to a point a short distance above the rail 13. The forward end of the guard frame forms a knuckle 10 to which a 55 gravity shoe 11 is pivotally secured by a pivot pin 11^a provided with the cotter pin

12 to prevent its accidental withdrawal from said knuckle and shoe. The gravity shoe is pivoted at a point off center so that its toe 60 normally projects upward or away from the rail 13 due to the greater weight of that portion of said shoe upon the opposite side of the pin 11^a. A latch 15 secured by pin 16 to the guard frame is adapted for frictional engagement with the forward end of the 65 journal box to prevent lateral movement of the said guard frame, a stop lug 17 serving to limit the movement of the said latch upon its pin 16. When it is desired to swing the guard frame to one side for any purpose the 70 forward end of the latch 15 is moved away from the stop lug thus disengaging the opposite end of the latch from the journal box and permitting the lateral movement of the 75 guard frame.

In operation the shoe 11 will contact with an object upon the rail 13 in advance of the wheel, this contact serving to depress the toe-end of the shoe and prevent the object from passing beneath the wheel. The shoe will, in 80 this position, pick up or project the object from the rail and entirely out of the path of the wheel after which operation the shoe will, through gravity, again assume its normal position.

What is claimed is:—

1. In a wheel guard for railway trucks, a guard frame hinged to the journal box, said guard frame extending forward, inward and downward and in advance of the wheels, 90 means carried by said guard frame for frictional engagement with said journal box to prevent lateral movement of said guard frame, and a shoe pivotally secured to the forward end of said guard frame. 95

2. In a wheel guard for railway trucks, a guard frame hinged to the journal box, said guard frame extending forward, inward and downward and in advance of the wheels, a latch carried by said guard frame for frictional engagement with one face of said journal box, and a gravity shoe pivotally supported off center at the forward end of said guard frame. 100

In testimony that I claim the foregoing 105 as my own I have hereto affixed my signature in the presence of two subscribing witnesses.

PETER FEIDEN, JR.
